(57) **CLAIM**

The ornamental design for a mobile phone case, as shown and described.

DESCRIPTION

FIG. 1 is a front elevational view of a mobile phone case showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, bottom, right side perspective view thereof;

FIG. 8 is rear, bottom, left side perspective view thereof;

FIG. 9 is a second front, bottom, right side perspective view thereof, with the pocket element shown detached from the case portion; and,

FIG. 10 is a second rear, bottom, left side perspective view thereof, with the pocket element in a flipped configuration, forming a 90 degree angle with respect to the case element. The broken line apertures represent unclaimed portions of the mobile phone case. The broken line stitching on the rear surface of the case element and on the pocket element represent claimed stitching.
